BASE PLATE FOR POSTS OR THE LIKE

Warren C. Weller, Camp Springs, Md., assignor to the United States of America as represented by the Secretary of the Army

Application February 27, 1953, Serial No. 23,811

Term of patent 14 years

(Cl. D28—1)

To all whom it may concern:

Be it known that I, Warren C. Weller, a citizen of the United States, residing at Camp Springs, in the county of Prince Georges and State of Maryland, have invented a new, original, and ornamental Design for a Base Plate for Posts or the like, of which the following is a specification, reference being had to the accompanying drawing, forming a part thereof.

Figure 1 is a perspective view of a base plate for posts or the like, showing my new design;

Figure 2 is an enlarged end elevation thereof;

Figure 3 is a front elevation thereof looking from the right of Figure 2; and

Figure 4 is a plan view thereof.

I claim:

The ornamental design for a base plate for posts or the like, substantially as shown.
